W. F. PERSONS,
AUTOMOBILE LAMP,
APPLICATION FILED DEC. 16, 1915.
1,214,582.

Patented Feb. 6, 1917.

UNITED STATES PATENT OFFICE.

WILLIAM F. PERSONS, OF LAKEWOOD, OHIO, ASSIGNOR TO THE GUIDE MOTOR LAMP MANUFACTURING COMPANY, OF CLEVELAND, OHIO, A CORPORATION OF OHIO.

AUTOMOBILE-LAMP.

1,214,582.

Specification of Letters Patent.

Patented Feb. 6, 1917.

Application filed December 16, 1915. Serial No. 67,118.

To all whom it may concern:

Be it known that I, WILLIAM F. PERSONS, a citizen of the United States, residing at Lakewood, in the county of Cuyahoga and State of Ohio, have invented a certain new and useful Improvement in Automobile-Lamps, of which the following is a full, clear, and exact description, reference being had to the accompanying drawings.

10 This invention relates generally to vehicle lamps, and more particularly to one intended for use upon automobiles and motor vehicles.

One object of the invention is to provide 15 an exceedingly simple and highly efficient means for retaining the glass front or lens in the body of the lamp and another object is to provide a simple and efficient means for shifting the focus of the light whereby 20 the intensity thereof can be regulated as desired.

With these objects and certain others which will become apparent as the description proceeds, the invention consists in the 25 novel features of construction, combination and arrangement, all of which will be fully described hereinafter and set forth in the appended claims.

In the drawing forming a part of this 30 specification Figure 1 is a vertical sectional view of an automobile lamp constructed in accordance with and embodying my invention; Fig. 2 is a detail view of the light shifting means; Fig. 3 is a detail perspective view of the split or divided retaining ring; and Fig. 4 is a detail sectional elevation illustrating the overlapped ends of said ring when in operative or locking position.

In the practical embodiment of my invention, I employ a lamp body 10, preferably of sheet metal, and represented as of a torpedo shape, but it will be understood that the lamp body can be made in any preferred or suitable design.

45 Near the front the body is given a slight inward curve as indicated at 11 and then shouldered as shown at 12, and the extreme outer end is rolled over as shown at 13, this rolled over portion being substantially equal to one half a circle in order that the extreme forward edge thereof may extend sufficiently inwardly to provide a firm seat or bearing for the inwardly extending portion of the retaining ring hereafter 55 more fully described.

The reflector 14 fits within the body of the lamp and is made upon a parabolic curve in order to secure the best results as a reflecting medium, and this reflector is provided with an outwardly extending rim 15 which rests upon the interior shoulder 11 and thereby positions the reflector within the body of the lamp, said reflector having a central opening for the socket of the lamp 16; and when needed, the reflector can have 60 an additional opening for the socket of the supplemental lamp 17.

If desired, a slight bead 18 may be produced at the juncture of the reflector and its flange or rim, but this is not essential. 70 The glass front or lens 19 is inserted in the lamp body and rests upon or contacts with the front of the reflector, there being preferably an interposed cushioning ring 20, of fiber or similar material, between the 75 flange of the reflector and the edge of the glass or lens.

For the purpose of firmly holding the glass or lens in its place within the lamp body, I employ a split or divided ring 21 80 which is constructed of sheet metal having sufficient rigidity and elasticity to permit the operations and perform the functions hereafter mentioned. This ring 21 is shaped with a considerable channel roll curve or 85 groove and along its outer edge is flanged as shown at 22, this flange 22 being at a slight angle to the adjacent curved or rolled portion, and this flanged portion 22 is adapted to fit beneath the inner edge of the rolled portion 13 of the lamp body, and when the flange 22 is so positioned between the 90 rolled edge 13, the inner edge 23 of the ring will be held firmly against the outer face of the glass front or lens and hold the same 95 rigid within the lamp body.

The ring 21 is slightly more than a complete circle so that when the ring is positioned in the front of the lamp body, the ends thereof will overlap, as most clearly 100 shown in Fig. 4, and the overlapping end is slightly upset as shown at 24 in order to accommodate the opposite end thereunder, and in practice I prefer to produce a notch or recess 25 opposite the upset shoulder 24 105 and also remove that portion of the flange 22 from the upset portion of the ring.

In operation the glass front or lens is inserted in the lamp body after the reflector has been properly arranged and the straight 110

end of the retaining ring has its flanged portion 22 inserted beneath the inwardly projecting edge of the rolled portion 13, and by proper manipulation the entire flanged portion of the retaining ring is forced into engagement with the rolled portion 13 and the upset end of the retaining ring will overlap the opposite end of said ring as most clearly shown, and by virtue of the fact that the 10 ring has considerable transverse curvature or is rolled throughout its entire length, the inner edge of said ring will be held firmly against the glass and the overlapping ends will also form a close connection with each 15 other by virtue of the inherent elasticity and rigidity of the metal shaped in the manner heretofore described.

The notch 25 is produced in the edge of the ring and the flange 22 removed from the 20 upset portion thereof in order to facilitate the manipulation of this end, as by the elimination of the flange and the provision of the notch or recess any convenient form of tool can be utilized for starting the end 25 of the ring from beneath the rolled front portion 13, and after the end has once been freed, the entire ring can be quickly and easily disconnected.

The incandescent lamp 16 is connected to 30 a socket member 30 which moves longitudinally in a sleeve 31 fastened to the lamp body at the central rear point and extending toward the reflector. Upon the outer end of this socket member 30 is a knob 32 by means 35 of which the socket carrying the lamp can be moved back and forth for the purpose of changing the focus of the light, as it is well known, that with the light properly positioned in a parabolic reflector, the rays of 40 light are thrown directly forward. This produces a glare, and in order to avoid this concentrating glare, it is necessary to shift the position of the light, and this is accomplished by moving the socket member 30 longitudinally in the sleeve 31, and for the purpose of maintaining the socket member and the lamp in the desired adjustment, I provide a series of serrations 33 in the socket member 30, which serrations are engaged by 45 a coil spring 34 held within an opening in the sleeve 31 by means of a clip or housing 50 secured to the sleeve 31, enveloping or extending over the coil spring 34 and holding the same properly positioned with reference to the sleeve; this spring permits the socket member to be pushed in or out, but at the same time has sufficient strength to hold the socket member locked at the desired point of adjustment. The sleeve 31 and 55 socket member 30 are cut away to permit the introduction of the proper terminals.

From the foregoing description taken in connection with the accompanying drawing it will be seen that I provide a simple and 60 easily assembled means for securing the

glass front or lens in the front of the lamp body and also that a simple and highly efficient means for changing the focus of the light is provided, and which does not interfere with the quick and easy arrangement of the reflector and parts dependent thereon. 70

Having thus described my invention, what I claim is:—

1. In a lamp, a divided retaining ring of spring sheet metal, said ring being channeled transversely and having a reversely extended flange along one edge extending at an angle to the adjacent portion of said ring. 75

2. In a lamp, a divided retaining ring of spring sheet metal and curved or channeled transversely, the ends of said ring overlapping, the overlapping end being offset, said ring having a reversely extended flange extending around the edge thereof except at the overlapping offset portion. 80

3. In a lamp, the combination with a lamp body having an inwardly rolled front edge, of a divided retaining ring having an outwardly extending flange bent away from the body portion of the rim and adapted to engage the inwardly rolled front of the lamp body. 85

4. In a lamp, the combination with a lamp body having an inwardly rolled front edge, of a divided retaining ring having an outwardly extending flange adapted to fit with in the inwardly rolled front edge of the lamp body, the ends of said divided retaining ring overlapping. 90

5. In a lamp, the combination with a lamp body having a rolled front edge, of a divided retaining ring having an outwardly extending flange adapted to engage the rolled edge of the lamp body, the ends of said ring overlapping. 100

6. In a lamp, the combination with a lamp body having a rolled front edge, of a divided retaining ring having an outwardly extending flange adapted to engage the rolled edge of the lamp body, the ends of said ring overlapping, the overlapping end being offset. 105

7. In a lamp, the combination with a lamp body having a rolled front edge, of a divided retaining ring having an outwardly extending flange adapted to engage the rolled edge of the lamp body, the ends of said ring overlapping, the overlapping end being offset, the offset portion being devoid of said flange. 110

8. In a lamp, the combination with a lamp body having a rolled front edge, of a divided retaining ring having an outwardly extending flange adapted to engage the rolled front of the lamp body, the ends of said ring overlapping, the overlapping end being offset, the offset portion being devoid of said flange, 115 a recess being produced in the edge of the ring at the offset shoulder.

9. In a lamp, a divided retaining ring of spring sheet metal curved transversely and having a reversely projecting flange extend- 120

ing around its outer edge, the inner edge projecting inwardly beyond said outer edge and flange.

10. In a lamp, the combination with a lamp body having a rolled front edge and an inwardly projecting shoulder adjacent said front edge, of a glass front or lens arranged within said lamp body and resting upon said shoulder and a divided retaining ring of sheet metal, said ring being curved or channeled transversely, the outer edge thereof being reversely curved and shaped for engagement with the rolled front of the body, the inner edge thereof contacting with the glass front or lens.

11. In a lamp, the combination with a lamp body having a rolled front edge and an inwardly projecting shoulder adjacent said front edge, of a glass front or lens arranged within said lamp body and resting upon said shoulder and a divided retaining ring of sheet metal, said ring being curved or channeled transversely, the outer edge thereof being reversely flanged and shaped for engagement with the rolled front of the body, the inner edge thereof contacting with the glass front or lens, the ends overlapping.

12. In a lamp, the combination with a lamp body having a rolled front edge and

an inwardly projecting shoulder adjacent 30 said front edge, of a glass front or lens arranged within said lamp body and resting upon said shoulder and a divided retaining ring of sheet metal, said ring being curved or channeled transversely, the outer edge 35 thereof being reversely flanged and shaped for engagement with the rolled front of the body, the inner edge thereof contacting with the glass front or lens, the ends overlapping, the overlapping end being offset.

13. In a lamp, the combination with a lamp body having a rolled front edge and an inwardly projecting shoulder adjacent 45 said front edge, of a glass front or lens arranged within said lamp body and resting upon said shoulder and a divided retaining ring of sheet metal, said ring being curved or channeled transversely, the outer edge 50 thereof being reversely flanged and shaped for engagement with the rolled front of the body, the inner edge thereof contacting with the glass front or lens, the ends overlapping, the overlapping end being offset and recessed along the outer edge, the overlapping end being devoid of said flange.

In testimony whereof, I hereunto affix my signature.

WILLIAM F. PERSONS.
